PRODUCING GAS AND COKE IN
CHAMBER OVENSCarl Otto, Essen, and Walter Stäckel,
Bochum, GermanyApplication November 14, 1932, Serial No. 642,680
In Germany November 14, 1931

6 Claims. (Cl. 202—23)

The invention relates to the production of gas and coke in chamber ovens and has for its object a process by which the gas yield of the ovens is increased. This object is achieved according to the invention by steam, tar, oil or other suitable substances or mixtures of such substances at the end of the carbonization period being supplied to the upper gas collecting space of the individual oven chambers, the gases being drawn off from the chambers in such a manner, that the said substances, viz. the steam or the like, have to travel a fairly long way through the hot charge of the coking chamber and are decomposed or converted during this passage. If steam is introduced, blue water gas is produced in this way, if tar is added to the steam, a carburetted water gas is obtained.

The horizontal or vertical intermittently operating chambers for the production of gas and coke usually have a tall rectangular cross section. In charging the chamber, a space is left free of fuel at top, which is used to draw off the distillation gases and usually communicates, adjacent one of its ends, with an ascension or gas off-take pipe. This upper gas collecting space is especially adapted for the supply of the substances to be converted according to the invention, such as steam, tar or the like, and for their distribution on the hot charge of the oven chamber, provided this upper space is shut off in a suitable manner during the conversion process from the ascension pipe, for example by means of a partition, or provided the substances to be converted are forced in another way not to enter directly from the upper gas collecting chamber into the ascension pipe, but to travel previous to this escapement an adequately long way through the coal cake.

Now the present invention affords a means for forcing the substances to be converted to travel such a way. To this end, according to the invention, a nozzle is provided through which these substances are fed to the upper gas collecting space of the coking chamber, and the outlet opening of the nozzle is turned away from the ascension pipe of the respective chamber so that the substances are blown out in a direction opposite to that which the distillation gases otherwise follow streaming towards the ascension pipe. If this nozzle is in the vicinity of the ascension pipe the substances introduced by the nozzle are distributed over nearly the whole surface of glowing coke. The substances to be converted may be supplied through the nozzle under such a pressure and at such a speed that by the injector effect thus obtained a greater pressure is produced in the great-

er portion of the upper gas collecting space than it prevails in the remaining portion thereof, to which the ascension pipe is connected, so that a certain circulation of the substances to be converted is obtained by this pressure difference. 5

The substances to be converted need not stream out of the nozzle in an exact horizontal direction, on the contrary, it may be of advantage to give the stream a slight inclination, that is to supply them downward at a slight angle to the horizontal. 10 The substances then better penetrate in the hot coal cake.

Obviously, with the quantity of substances to be converted supplied to the upper gas collecting space in the unit of time also increases the pressure above atmospheric prevailing in said space. Since this space is inclosed by refractory brick-work of a nature so as to allow a certain transition of gases, not too high pressures above atmospheric must act on it. In order, however, to supply, despite this, large quantities of these substances to the upper gas collecting space, it has been proved advantageous to provide two or more supply nozzles one behind the other in the upper gas collecting space. If for instance two nozzles 25 are provided, the possibility is given, by an adequate supply of steam to that nozzle which is nearest to the ascension pipe, to influence the pressure prevailing in the vicinity of the ascension pipe without the effect of the other nozzle 30 and thus the quantity of steam supply by the latter being altered. Furthermore, by correspondingly regulating the nozzle which is nearest to the ascension pipe, the pressure prevailing in the vicinity of the latter can be kept constant but the 35 quantity of steam fed through the other nozzle can be varied within wide limits. Probably, the effect of a second nozzle is due to the fact that with increasing supply also the suction effect of the first nozzle increases correspondingly, but that the drop of pressure thus produced by the effect of this nozzle can be compensated for behind the nozzle by a suitable steam supply through the second nozzle. 40

The nozzle may be designed in a manner so 45 as to supply simultaneously steam and a carbureting agent into the upper gas collecting space, but it is advisable to withhold the supply of tar and oils until the charge of the respective chamber has cooled down to a temperature of 50 about 900° centigrade by the mere supply of steam and the endothermic formation of water gas thus caused. With some carbureting agent it has proved advantageous to convert the steam and the carbureting agent successively and separate- 55

ly, because it may happen that these two conversion processes disturb one another. If two nozzles are provided the one nearer to the ascension pipe may serve for spraying tar upon the 5 glowing surface of coke while steam is introduced through the other nozzle. The means for supplying the steam and the tar may further be designed in such a manner that the substances to be converted are preheated by the heat radiated 10 by the hot walls of the coking chamber.

By the generation of water gas in the cooking chamber not only is the advantage afforded of the gas yield of the charge being increased, but also the further advantage that part of the sulphur 15 existing in the coke is converted sulphur containing acid by the hydrogen in a nascent state and is taken up by the gas, from which it can easily be separated in any suitable known manner. In this way the sulphur percentage of 20 the coke is lowered, which is of very great importance for the use of the coke for metallurgical purposes.

Apparatus for use in the practice of the invention is illustrated in the accompanying drawing 25 in which Fig. 1 is a vertical section on the longitudinal central plane of an intermittently operating horizontal coking chamber; and Fig. 2 is a partial section, taken similarly to Fig. 1, illustrating a form of injection nozzle differing from 30 the nozzles shown in Fig. 1.

In the drawing, *a* are the doors at the end of an oven chamber containing a charge *b* and having a gas collection space *c* above the charge. As shown the gases pass out of the chamber through 35 an ascension pipe *d* to the collecting main *e*, the ascension pipe being connected to the space *c* adjacent one end of the latter. A plurality of charging openings *h* are formed in the top wall 40 of the chamber, the openings being distributed *g* along the length of the chamber. As shown, there are two nozzles *i* in the gas collecting space *c*, each nozzle being at the ends of a corresponding branch *m'* from piping *m*, individual to the oven chamber end connected through a valve *k* 45 to a supply pipe *n*. The said branch pipes pass axially through special covers *f* for the corresponding charging openings *h*. As shown, the pipe branch to which one of the nozzles *i* is connected, extends through the charging opening *h* 50 adjacent the end of the oven chamber at which the ascension pipe is located, and the branch pipe carrying the other nozzle *i* extends, through the adjacent charging opening. The branch pipes *m'* are bent so that the stream of fluid 55 discharged by each nozzle *i* into the gas collection space *c* is directed away from the end of the chamber at which the ascension pipe is located. As indicated by the arrows, each stream is slightly inclined downwardly, so that the fluid discharged 60 impinges against the top of the charge *b* along approximately the entire length of the space *c* except for a portion adjacent the ascension pipe. The direction of gas flow through the charge is indicated by the arrows.

In operation, the nozzles are not inserted into the oven chamber until after the charge therein has reached a temperature of 900° or 1,000° C. When the nozzles are inserted the special covers 70 *f* replace the regular covers *f'* previously closing the charging openings *h* through which the nozzles are inserted. The fluid supplied by the pipe *m* through the nozzles *i* may be steam or some carbureting agent such as tar, oil or other 75 suitable substances or mixtures, and the nozzles

may be employed to introduce steam at one time and a carbureting agent at another time.

The special nozzle *o* shown in Fig. 2, may be employed to discharge an atomized mixture of steam and tar or other carbureting agent. The latter is supplied through a pipe *m*² axially disposed in, but not filling a pipe *m*³ through which steam is supplied.

We claim:

1. The process of increasing the gas yield in 10 the operation of a chamber oven producing gas and coke from a charge of solid carbonizable material by heating said charge to a temperature above 900° centigrade in a chamber having an upper gas collecting space, said process consisting in first introducing steam into the upper gas collecting space of the chamber until the temperature of the charge of the chamber has lowered to about 900° centigrade, and thereupon introducing tar in finely divided state. 15

2. The process of increasing the gas yield in 20 the operation of a chamber oven producing gas and coke from a charge of solid carbonizable material by heating said charge to a temperature above 900° centigrade in a chamber having an upper gas collecting space, said process consisting in first introducing steam into the upper gas collecting space of the chamber until the temperature of the charge of the chamber has lowered to about 900° centigrade, and thereupon alternately introducing tar in finely divided state and steam. 25

3. The process of increasing the gas yield in 30 the operation of a chamber oven producing gas and coke from a charge of solid carbonizable material by heating said charge to a carbonizing temperature in a chamber having an upper gas collecting space, which consists in withdrawing from a localized portion of said space gas entering the latter from the subjacent charge while the latter is heated to a carbonizing temperature, and simultaneously introducing into said space a substance in vaporous form and adapted to react with the hot charge and thereby form gas, said substance being introduced into said space partly, 35 at least, in a stream directed away from said localized portion, and creating a pressure in the portion of said space entered by said stream which is higher than the pressure in said localized portion, whereby a gas flow, downward into the 40 charge from the portion of said space in which the pressure is increased by said stream and upward from the charge into said localized portion of said space, is produced. 45

4. The process of increasing the gas yield in 50 the operation of a chamber oven producing gas and coke from a charge of solid carbonizable material by heating said charge to a carbonizing temperature in a chamber having an upper gas collecting space, which consists in withdrawing 55 from a localized portion of said space gas entering the latter from the subjacent charge while the latter is heated to a carbonizing temperature and simultaneously introducing into said space a substance in vaporous form and adapted to react with the hot charge and thereby form gas, said substance being introduced into said space partly, at least, in a stream directed away from said localized portion and downwardly inclined, and creating a pressure in the portion of said 60 space entered by said stream which is higher than the pressure in said localized portion, whereby a gas flow, downward into the charge from the portion of said space in which the pressure is increased by said stream and upward from the 65 charge into said localized portion of said space, is produced. 70

charge into said localized portion of said space, is produced.

5. The process of increasing the gas yield in the operation of a chamber oven producing gas and coke from a charge of solid carbonizable material by heating said charge to a carbonizing temperature in a chamber having an upper gas collecting space, which consists in withdrawing from a localized portion of said space gas entering the latter from the subjacent charge while the latter is heated to a carbonizing temperature and simultaneously introducing into said space a substance in vaporous form and adapted to react with the hot charge and thereby form gas, 10 said substance being introduced in two streams entering said space at different distances from, and each directed away from said localized portion, and creating a pressure in the portion of said space entered by said streams which is higher 15 than the pressure in said localized portion, whereby a gas flow, downward into the charge from the portion of said space in which the pressure is increased by said streams and upward from the charge into said localized portion of said space, is produced.

6. The process of increasing the gas yield in the operation of a chamber oven producing gas and coke from a charge of solid carbonizable material by heating said charge to a carbonizing temperature in a chamber having an upper gas collecting space, which consists in withdrawing from a localized portion of said space gas entering the latter from the subjacent charge while the latter is heated to a carbonizing temperature and simultaneously introducing a stream of steam 10 and a stream of finely divided tar into portions of said space displaced from said localized portion by greater and lesser distances respectively, each of said streams being directed away from said localized portion, and creating a pressure in 15 the portion of said space entered by said streams which is higher than the pressure in said localized portion, whereby a gas flow, downward into the charge from the portion of said space in which the pressure is increased by said streams 20 and upward from the charge into said localized portion of said space, is produced.
